UNITED STATES PATENT OFFICE

2,311,442

REFRIGERATOR JACK

Charles S. Johnston, Glencoe, Ill., assignor to
Transportation Specialties Company, Chicago,
Ill., a corporation of Illinois

Application May 8, 1941, Serial No. 392,513

27 Claims. (Cl. 280—46)

The present invention relates to refrigerator jacks, and is particularly concerned with jacks for refrigerators adapted to be used for less than carload shipments of perishable products.

One of the objects of the invention is the provision of an improved refrigerator, having means for facilitating its movement into such a position in a railway freight car that a multiplicity of the refrigerators may be so arranged in the car as to utilize the space most effectively.

Another object of the invention is the provision of an improved refrigerator for less than carload shipments of perishable products, which is adapted to be handled as a unit so that it may be placed in a railway freight car as such, and it may be removed from the car by means of its associated equipment, and delivered as a unit with its perishable products intact and in good condition.

Another object of the invention is the provision of an improved supporting structure for refrigerators of the class described, by means of which the refrigerator is adapted to be held in relatively fixed position in the car by virtue of its weight and the engagement of its lower structure with the floor of the car and by means of which the refrigerator is adapted to be loaded or unloaded as a unit without necessity for using other wheeled vehicles.

Another object of the invention is the provision of an improved jacking arrangement for refrigerator units by means of which the refrigerator may be supported upon one or more wheels, or it may be permitted to come to rest upon legs which will engage the floor and hold the refrigerator in relatively fixed position with respect to the car floor or other support upon which it is located.

Another object of the invention is the provision of an improved jacking arrangement of the class described, by means of which the elements of the jack may be latched in such position that the adjacent portion of the refrigerator is supported upon wheels or the elements may be unlatched and the weight of the refrigerator deposited on legs which engage the floor.

Another object of the invention is the provision of an improved jacking arrangement which is adapted to be moved into such a position underneath the refrigerator that there are substantially no projecting parts which might interfere with the close packing of the refrigerator units in a storage space, such as a freight car or a warehouse.

Another object of the invention is the pro-

vision of a refrigerator unit having a jacking arrangement provided with a handle by means of which the weight of the refrigerator may be transferred to wheels and the unit may be moved about, and in which the handle and jacking arrangements are adapted to be movably mounted so that they can be moved into an inoperative position where the handle will not interfere with the location of other units in such manner as to use all of the storage space available.

Other objects and advantages of the invention will be apparent from the following description and the accompanying drawings, in which similar characters of reference indicate similar parts throughout the several views.

Referring to the accompanying drawings, of which there are eight sheets:

Fig. 1 is a front elevational view of a refrigerator unit embodying the invention;

Fig. 2 is a side elevational view of the embodiment disclosed in Fig. 1;

Fig. 3 is a rear elevational view;

Fig. 4 is a diagrammatic plan view of a railway freight car in which a plurality of the refrigerator units have been so arranged as to utilize the space available most effectively;

Fig. 5 is a fragmentary vertical sectional view, taken on the plane of the line 5—5 of Fig. 6, looking in the direction of the arrows, showing the details of construction of a jacking arrangement for one end of the refrigerator unit;

Fig. 6 is a fragmentary front elevational view of the jacking arrangement of Fig. 5;

Fig. 7 is a view similar to Fig. 5, with the parts in the position which they assume in the beginning of the lifting movement of the jack;

Fig. 8 is a view similar to Fig. 5 of the jacking mechanism in the position which it assumes at the end of the lifting movement of the jack, with the mechanism latched;

Fig. 9 is a simplified diagrammatic fragmentary sectional view, showing the parts of the jack mechanism in the position of Fig. 5, with certain of the elements omitted for the purpose of clarity, taken on the plane of the line 9—9 of Fig. 6, looking in the direction of the arrows;

Fig. 10 is a view similar to Fig. 9, taken on the plane of the line 10—10 of Fig. 6, showing other details of structure of the parts;

Fig. 11 is a sectional view, taken on the plane of the line 11—11 of Fig. 6, looking in the direction of the arrows;

Fig. 12 is a sectional view, taken on the plane of the line 12—12 of Fig. 5, looking in the direction of the arrows;

Fig. 13 is a fragmentary sectional view, taken on the plane of the line 13-13 of Fig. 5, looking in the direction of the arrows;

Fig. 14 is a fragmentary sectional view, taken on the plane of the line 14-14 of Fig. 5, looking in the direction of the arrows;

Fig. 15 is a fragmentary sectional view of a part of the handle structure, taken on the plane of the line 15-15 of Fig. 2, looking in the direction of the arrows;

Fig. 16 is a transverse sectional view of the handle, taken on the plane of the line 16-16 of Fig. 15, looking in the direction of the arrows;

Fig. 17 is a sectional view, taken on the plane of the line 17-17 of Fig. 1, looking in the direction of the arrows.

Referring to Fig. 1, 20 indicates one of a plurality of refrigerator units which are preferably made of such size that a given number of the units will substantially fill a railway freight car of standard size; for example, those of Fig. 4, indicated by the numerals 20-27, being shown in a standard railway car 28, which may be completely filled, if desired, by locating one additional unit in the remaining space 29.

Thus the refrigerator units are preferably of such width that two of them arranged side by side will use substantially all of the space in one end of the car, with some clearance between each of the units and the walls and between the two units themselves.

The refrigerator units are preferably made longer than they are wide, and the height is preferably sufficient to permit the hanging of meat, such as quarters of beef, etc., from a rack carried in the top of the unit.

The refrigerator unit preferably comprises a pair of complete and separate metal shells, one on the inside, and the other on the outside, separated and insulated by layers of rigid insulation under compression, so that there is no metal-to-metal contact between the inner and outer metal layers, and the interior of the unit is well insulated.

Each unit is provided with a front door opening 30, closed by a door 31 of the same construction, having inner and outer metal layers insulated from each other in the same way, the door being supported by means of the hinges 32 and locked by means of the locks 33.

The refrigerator is provided with a metal container for receiving a refrigerant, such as solid carbon dioxide, and the container preferably has only a predetermined area exposed to the air inside the refrigerator, the balance of the area of the container being insulated so as to limit the use of the solid carbon dioxide and extend its use over a long period of time.

The detailed structure of my refrigerator unit is made the subject of a separate application for patent, filed June 11, 1941, Serial No. 397,557.

The supporting framework of the refrigerator unit preferably comprises four inwardly open channel members 34, 35, 36, 37 arranged in a rectangle, with their flanges extending inwardly, the corners being welded together.

The rectangular framework comprising the open channel members 34, 35, 36, 37 is preferably longer than it is wide as indicated by the length shown in Fig. 2 and shown in Fig. 1 and this framework preferably supports a pair of oppositely turned channel members 54, 55 serving as a guide for the front wheels and jack. The guide channels 54, 55 (Fig. 6) have their ends secured at one end to the channelled member 36 by weld-

ing and at the other end to the channelled member 37 by welding. Channelled guide members 54, 55 have their horizontal flanges 56, 57 slightly spaced from each other as shown in Fig. 6.

The rear wheels are adapted to be supported by a pair of transversely extending channelled members 38 (Fig. 2). Each of these transversely extending channelled members has horizontally extending attaching flanges 39 and 40 and each of these channelled members 38 extends from the side frame member to one of the guide channels 54 or 55. Thus each channelled member 38 for supporting the rear wheels has one end secured to a side frame member such as 34 and the other end secured to a channelled member such as 54, the other one being secured to side frame member 35 and channelled member 55 by welding or other convenient fastening means.

These attaching flanges may be secured to the horizontal flange 41 of a wheel frame 42 by means of screw bolts 43, passing through the flanges 39, 40 and 41.

Each wheel frame may be identical in structure and may comprise the upper attaching flange 41, a pair of depending bearing flanges 44, each having an aperture 45 for a pintle 46. The pintle 46 passes through the bearing of a metal wheel 47, having a relatively wide bearing surface at its periphery, and the pintle 46 may be riveted over at its ends.

A plurality of the wheels 47 and wheel frames 42 are preferably located adjacent the rear end of the refrigerator unit, but slightly spaced therefrom, as shown in Fig. 2. At its forward corners, below the door 31, the supporting frame for the refrigerator unit is preferably provided with a pair of legs 48, 49.

Each of these legs may comprise a pair of flanges 50, 51 at right angles to each other, and the flanges may taper in width toward the bottom of the leg. At the top the flanges 50, 51 engage the outside of the channels 34, 36 and 36, 35, to which they are welded along each of the edges of the channels and of the leg flanges so as to secure the legs firmly to the lower frame.

The legs 48, 49 are of such length that when the refrigerator is supported upon them its floor is in substantially level position. By means of the engagement of the lower flanges of the legs 48, 49 with the car floor, the refrigerator unit is prevented from rolling in the freight car and is held in relatively fixed position. The unit is relatively heavy, and therefore the legs have firm engagement with the floor.

The refrigerator unit is preferably provided with a jack so attached to the unit that it may be utilized in the position of Fig. 5, or it may be moved into a storage position, under the unit. This jack is indicated in its entirety by the numeral 52, and it is provided with a jack handle 53. The jack may be slid backward under the refrigerator when not in use.

For this purpose the lower framework of the refrigerator unit, comprising the channels 34-37, is provided with a pair of horizontally extending channelled members 54, 55. These channelled members may extend the full length of the lower frame and may have their ends secured to the channelled members 36, 37 by welding.

The channelled members 54, 55 have their flanges extending toward each other, and the lowermost of these flanges, indicated by the numerals 56, 57, are adapted to serve as guides for a slider, indicated in its entirety by the numeral 58.

The slider 58 is adapted to provide a support for a pair of pivoted wheels 59, 60 and for the jack, indicated in its entirety by the numeral 52 (Fig. 2). The slider 58 comprises a main body plate 61, which may be of substantially rectangular shape, and which is located below the guide flanges 56, 57. At its rear or left end in Fig. 5, the slider plate 61 is provided with a pair of apertures 62 for receiving a pair of screw bolts 63, 64. These bolts pass through the apertures 62 and through a rectangular spacer block 65, which is provided with a pair of registering apertures, and the bolts also pass through an upper bearing plate 66, having registering apertures.

The spacer block 65 is preferably of a greater thickness than the thickness of the lower guide flanges 56, 57 of the channelled members 54, 55, so that there is a clearance, indicated by the space shown in Fig. 6, at 67.

The spacer block is of sufficient width to be slidably received between the flanges 56, 57, with a suitable clearance, while the bearing plate 66 is of the same width, but of greater length, and overhangs the guide flanges 56, 57, as shown in Fig. 6.

The members 61, 65, 66 are preferably secured together tightly by means of the bolts 64, 63 and spring washers, as shown in Figs. 5 and 14.

Referring to the opposite end of the slider plate 61, they are also provided with a pair of apertures for receiving the bolts 68, 69 (Fig. 14), which again pass through a similar bearing plate 70, overhanging the guide flanges 56, 57.

A similar spacing block 71 is secured in a similar way by means of the bolts 68, 69, and the members 70 and 71 are fixedly secured together by means of nuts on the ends of the bolts 68, 69.

In this case the apertures for the rivets 68, 69 are disposed forwardly of the center line of the bearing plate 70 and spacer block 71 in order to provide space for a larger series of registering bores 73, 74, 75 (Fig. 5.) These bores are adapted to receive the pivot bolt 76 by means of which the wheel frame, indicated at 77, is pivotally mounted on the slider 58.

The wheel frame 77 preferably comprises an upper bearing plate 78, having a plane surface adapted to be slidably engaged with the lower plane surface of the slider plate 61. The bearing plate 78 likewise has a centrally located aperture, which may be provided with a bearing bushing 79 for receiving the pivot bolt 76.

The pivot bolt 76 is provided with a washer 20, engaging its head and engaging below the bearing plate 78, and at its upper threaded end with a nut 81 secured in place by means of a cotter pin 82 engaging the shoulders of a slot in the nut 81 and passing through an aperture in the bolt 76.

The wheel frame 77 carries the front wheels 59, 60 and the structure of the jack 52, and the jack is adapted to be used in the position of Fig. 5, or it may be shoved back under the refrigerator, the refrigerator being supported by its legs 48, 49, in the position of Fig. 2.

The slider 58 supports the wheels and jack in such manner that the entire assembly of slider, jack, and wheels may be slid on the guides 56, 57 from the front position of Fig. 5 to the rear position (not shown). During this sliding movement the carriage is suspended from the guide flanges 56, 57 in the position of Fig. 6, the clearance 67 being below the guide flanges 56, 57, but the wheels rest on the floor.

The guide flanges 56, 57 are preferably pro-

vided with stop means for automatically securing the jack in the forward position of Fig. 1 or Fig. 5, while the jack is being used.

This stop means comprises one or more stop members 83 (Fig. 2) carried by the guide flanges 56, 57, and of less width than the clearance at 67. The stop member 83 depends below the guide flanges 56, 57 so that when the wheels and jack depend from the guide flanges 56, 57 the slider 58 may be slid backward without engaging the stop members 83.

When, however, the wheels 59, 60 engage the floor and support the weight of the jack, and the bearing plate 61 is moved up into engagement with the lower surfaces of the guide flanges 56, 57, the slider 58 is prevented from moving backward because the slider plate 58 will engage the stop member 83.

Thus, whenever the refrigerator is supported upon its forward wheels, the slider, with the jack and pivotally mounted wheels, is pivotally secured in its forward position. There is no possibility that a push on the jack and forward wheel frame will cause the wheels to recede under the refrigerator at this time because of the engagement with the stop member 83.

Referring to Fig. 6, the plate of the wheel frame 77 is preferably provided with a pair of depending flanges 84, 85, comprising a pair of metal plates, having their upper edges secured to the bearing plate 78 by welding or otherwise.

These depending flanges 84, 85 are parallel to each other, and they may be secured together at the front straight edge by means of a transverse plate 86, welded to the bearing plate 78 at the top and at both lateral edges to the depending flanges 84, 85.

The rear edge of each of the depending flanges 84, 85 may be straight, as indicated at 87; but the lower outline is slightly irregular, as indicated at 88, to provide suitable clearance between these depending flanges and the wheel shaft 89, further to be described.

At their lower rear corners the depending flanges 84, 85 are provided with a pair of aligned apertures 90 for receiving the stub shaft 91, which may have a cotter pin 92 in each end inside the flanges 84, 85. The stub shaft 91 pivotally supports a foot latch, indicated at 93 (Fig. 5).

The foot latch 93 may comprise a pair of elongated metal plates 94, 95 secured in spaced relation and parallel to each other, by means of the foot-engaging plate 96, which is welded to the upper edges of the plates 94, 95 and curves downward over the curved end 97 of the plates 94, 95.

A downwardly turned flange 98 of this foot plate also serves to hold the plates 94, 95 in parallel relation, being welded to them.

The main body of the foot latch plates 94, 95 tapers in width from a latching shoulder 99 to the curved end surface 97. The latching shoulder 99 extends substantially transversely to a radial line drawn from the center of the shaft 91 to the surface 99, but is preferably provided with a slight angular divergence from the tangential position, as will be observed by the eye in Fig. 5.

The relatively straight latching shoulder 99 forms part of a curved partially circular recess 100 in the latching plates 94, 95 and the recess 100 is of a suitable size to receive a portion of the wheel shaft 89.

From the recess 100 the latching plates 94, 95 increase in width toward the left end in Fig. 5 to provide sufficient body for the bearing apertures 90. A spring supporting plate 101 extends

transversely between the two latching plates 94, 95, and is welded to both of them and is provided with an aperture 102 for receiving the hook end of a helical spring 103.

The opposite end of the spring 103 is hooked into an aperture in an angle bracket 104, which is welded to the lower rear side of the bearing plate 78 (Fig. 5). The spring 103 is under initial tension, and it urges the foot latch 93 upward to the position of Fig. 5, so that it is urged into latching position, but may be released by means of foot pressure on the foot plate 96.

The two depending plates 84, 85 are also provided with a pair of aligned apertures 105 (Fig. 5) located forwardly of each plate, and approximately midway between the upper and lower parts of the plate.

These apertures rotatably support a stub shaft 106, which has cotter pins 107 passing through each end of the shaft, inside each of the depending flanges 84, 85, to retain it against axial movement.

The stub shaft 106 pivotally supports a pair of link plates 108, 109 (Fig. 6). Each link plate 108, 109 is provided with an aperture at its rear end for receiving the stub shaft 106. At its forward end each link plate is provided with an aperture for receiving the wheel shaft 89.

Thus the wheel shaft 89 is supported by the wheel frame 77 through the intermediary of the pivotally mounted links 108, 109 so that the wheels may move to the position of Fig. 5, where they merely rest on the floor, but support no weight other than that of their associated parts, or the position of Fig. 8, in which the links 108, 109 are pivoted downward, and the wheels support the refrigerator.

The link plates 108, 109 comprise elongated flat metal plates with straight sides and semi-circular ends.

The wheel shaft 89 is of sufficient length to extend beyond the depending flanges 84, 85 at each side through parts of the handle to support the wheels 59 and 60 at each end of the shaft 89.

Each end may be threaded and provided with a suitable washer and nut 110, 111 secured in place by means of a cotter pin 112 passing through the shaft. The wheels 59, 60 are preferably standard truck wheels provided with roller bearings for supporting the wheels on the shaft in order that the refrigerator unit may be moved with a minimum amount of effort.

In the same manner the wheels 47 at the rear of the refrigerator unit may be provided with roller bearings supporting the wheels on the shafts 46.

The wheel shaft 89 also supports the handle 53, which will now be described in detail. The handle 53 is preferably constructed of a pipe or tubular metal member 113 at its upper end, the pipe being welded to the parallel attaching flanges 114 of a pair of metal legs 115, 116.

The legs 115, 116 are bent out at 117 to extend outwardly from each other and are bent again into parallel relation at 118 (see Fig. 1). These legs comprise elongated metal plates, which are of the same width throughout the major portion of their length, but are widened at the lower end, as indicated by the outwardly curved outline at 119 in Fig. 5.

Each of the legs 115, 116 is provided at the rear part of its enlargement with an aperture 121 for receiving the wheel shaft 89. The shape of the aperture 121 is best shown in Fig. 9, and

this aperture may be said to be of substantially a flattened heart shape. The aperture 121 is formed at the top with a pair of downwardly open recesses 122, 123, separated by a rounded point or hump 124.

The recesses 122, 123 are of substantially the same curvature as the wheel shaft 89, which they are adapted to receive. The lower part of the aperture 121 is curved on a larger radius so as to join the circular portions 121, 122 at the bottom with a more gradually curved portion 125, which is spaced sufficiently from the hump 124 to permit the wheel shaft 89 to move from the recess 122, past hump 124, to the recess 123.

The enlargement 120 of the handle legs 115, 116 is also provided with what may be termed a radial extension with respect to the shaft 89, when it is located in the recess 123, this extension being indicated at 126.

The extension 126 is formed with an upwardly open circular groove or recess 127 adapted to fit or receive the stub shaft 106 (Fig. 9), on which the links 108, 109 are pivoted. The relation of the parts and the length of the links 108, 109 is such that when the handle has its aperture 121 so disposed that the wheel shaft 89 is in the recess 122, the handle may be pivoted downward or upward, and the curved edge 128 of the extension 126 is adapted to clear the stub shaft 106. Thus the handle may be pivoted as desired, and held at any desired height, without bringing the shoulder or recess 127 into engagement with the stub shaft 106.

When the handle legs 115, 116 have their apertures 121 disposed in such a position that the wheel shaft 89 is in the recess 123, then a pivotal movement of the handle on the wheel shaft will bring the recess 127 into engagement with the stub shaft 106 in the manner shown in Fig. 7 for the purpose of using the handle as a jack handle in a manner further to be described.

At its upper end the handle 53 is provided with a transverse bore 131, having a metal tube or pipe 130, which has a tight frictional fit in the bore 131 and serves as a hand grip. The handle (Figs. 2 and 15) is also provided with a longitudinally extending slot 132 in the right side of the pipe 113 (Fig. 1) adapted to receive and guide a rod 133, which serves as the handle for a shift lever rod 134, located in the pipe 113 of the handle 53.

The rod 133 is threaded into a threaded bore 135 in a guide block 136, which is welded to the upper end of the rod 134. The rod 134 is bent laterally at 137 (Fig. 1), where it emerges from the pipe 113, and has the attaching flange 138 of another leg or rod welded to it, just above this end.

The two legs 139 of the rod 134 then extend diagonally outward, and are bent again at 140 into parallel relation, so that they are located just inside the legs 115, 116 of the handle. The two legs 141, 142 of the rod 134 are bent inwardly at 143 toward each other (Fig. 6), and the end of each rod is provided with an aperture 144 for receiving a cotter pin 145 and washer 146 to retain the rod in the bore 147 of shift lever 148.

The arrangement at each side of the handle is the same, and the other shift lever has been indicated by the numeral 149 (Fig. 6). One of the shift levers 148 is shown in elevation in the section of Fig. 10, and each of these shift levers 148, 149 comprises a substantially triangular

metal plate, the three sides being indicated by the numerals 150, 151, 152.

Each shift lever is provided with a bore 153 located in the upper corner of the shift lever, and the shift lever is pivotally mounted on the enlargement 120 of the handle leg 115 by means of the cap screw 154, having head 155.

Each shift lever 148, 149 is provided with an oblong aperture 156 (Fig. 10) formed by the two straight sides 157, 158, having the half circular ends 159, 160. The size of these circular ends and the spacing between the flat sides of the oval aperture 156 is sufficient so that the wheel shaft 89 may pass through the oval aperture 156 of each shift lever 148, 149.

The shift levers 148, 149 are each provided with an offset 161 (Fig. 10) by means of which the rods 141, 142 may be located immediately adjacent the handle legs 115, 116, and the shift levers 148, 149 may also be pivoted on the handle legs 115, 116 and pivotally engaged with the rods 141, 142.

The operation of the jack in the lifting of the front end of the refrigerator unit is as follows: The jack is drawn forward as far as possible on the guide flanges 56, 57 to the position of Fig. 1. Ordinarily the parts of the jack will at this time be in the position of Fig. 5, and the relation of the parts at this time is such that the handle 53 may be moved pivotally on the wheel shaft 89, located in recess 121 of each handle leg, to any desired elevation. Assuming the refrigerator has been jacked up on its front wheels, the handle may be disposed in vertical position, or it may be pivoted downwardly until the handle bar 130 is at the desired elevation for the operator, who expects to pull or push the refrigerator from place to place.

As the recesses 122, 123 are disposed in the upper side of the handle enlargement 120 and there is a hump 124 between them, the handle tends to remain by gravity in whichever position it happens to be with respect to the location of the wheel shaft 89 in recess 122 or 123.

The same is true of the handle with respect to the location of the shaft 89 in recess 122 when the handle is pivoted downward, out of engagement with the jack mechanism. Then the weight of the pivoted end of the handle keeps the wheel shaft 89 in the left end of the recess 122. It is only by means of the shifting levers 148, 149 pivoted on the handle and acting against the wheel shaft that the handle may be shifted at will from one recess 122 to the other 123.

The oblong slot 156 in the shift lever is required to provide suitable clearance for the wheel shaft as it is moved by the shift lever from one recess to the other.

The handle may be moved downward to the horizontal position, as shown in Fig. 8, and the jack may be slid under the refrigerator on the guides 56, 57. At this time the refrigerator is resting at its forward end on the legs 48, 49.

The shift lever links being in their uppermost position in Fig. 5, these shift levers 148, 149 tend to confine the wheel shaft 89 in the recesses 122 (Fig. 9) of the handle enlargement 120. When it is desired to jack up the refrigerator, the shift levers 148, 149 may be pivoted in a counter-clockwise direction with respect to the handle legs, by pulling upward on the handle rod 133.

The two legs 141, 142 of this connecting rod will then move the shift levers 148, 149 clockwise on the handle legs from the position of Fig. 5 to that of Fig. 7. This causes the wheel shaft 89 to be shifted from its position in Fig. 5 in the recess

122 (Fig. 9) to the new position of Fig. 7 in the recess 123 (Fig. 9).

In effect, the moving of the shift lever moves the lower end of the handle in a horizontal direction on the wheel shaft 89. The recess 127 (Fig. 9), which is disposed in Fig. 5 in such position radially of the wheel shaft 89 that it will miss the stub shaft 106, thus becomes moved to the position of Fig. 7, where a pivotal movement of the handle on the wheel shaft 89 causes the recess 127 to engage the stub shaft 106.

The stub shaft 106 provides a pivotal mounting for the links 108, 109 on the wheel frame 17, which is attached to the lower part of the refrigerator by means of the pivot bolt 76. If the handle 53 is then moved in the direction of the arrow in Fig. 7, the handle will be caused to bear down on the wheel shaft 89 at the recess 123 of the handle enlargement 120 and to bear up on the stub shaft 106, and the refrigerator unit, by means of the groove 127. The handle is now in position to pry the refrigerator upward, using the wheel shaft as a point of pivotal movement. The continued downward movement of the handle 53 from the position of Fig. 7 to a horizontal position of the handle will eventually bring the links 108, 109 into approximate vertical position, as shown in Fig. 8, at which time the weight of the refrigerator has been lifted from the legs 48, 49 and transferred to the wheels 59, 60.

When the links 108, 109 have pivoted downward to such a position that the wheel shaft 89 moves from the position of Fig. 7 to that of Fig. 8, where it is disposed in the recess 100 of the foot latch levers 93, these latching levers will be moved upward by the spring 103 until the shoulder 99 engages the wheel shaft 89 to hold the wheel shaft in that position.

Thereafter the handle 53 may be lifted at its handle bar 130, and the wheel shaft will be retained in the latched position of Fig. 8 by the foot latch 93. As the handle is lifted by means of its cross bar 130, the enlargement 120 will have its recess 127 withdrawn by counterclockwise rotation from the stub shaft 106.

The prying pressure, which has kept the handle enlargement 120 in such position that the wheel shaft engages in recess 123, being held there by the hump 124 and the engagement of the stub shaft 106 in recess 127, is relieved, and the enlargement 120 of the handle then drops on the wheel shaft from the position in which the wheel shaft is in the recess 123 to the position of Fig. 8, where the wheel shaft is in the recess 122 of the heart-shaped aperture 121 in the handle enlargement 120.

Now the handle may be pivoted to any desired position without affecting the jack, and the refrigerator unit is supported on pivot wheels in front and on the plurality of wheels at the rear, and it may be maneuvered like any truck, by means of the handle.

After the truck has been moved into the desired position in the freight car or in any other storage space, the weight of the refrigerator may be removed from the front wheels 59 and 60 and placed on the legs 48, 49, irrespective of the position of the handle by merely stepping on the foot pedal 93.

This will cause the clockwise movement of the foot latch 93 from the position of Fig. 8 to that of Fig. 5, and the wheel shaft 89 may move forward from the position of Fig. 8 to that of Fig. 5. As the wheel shaft moves forward, the front end 75 of the refrigerator unit moves downward with

the stub shaft 106, the links 108, 109 pivoting counterclockwise. The handle itself is not affected because it has its enlargement in the position of Fig. 8, where the wheel shaft 89 is in the recess 122 and the prying shoulder 127 has been moved radially away from the stub shaft 106.

The unlatching of the jack cannot react against the handle and give the handle a push because the handle is disconnected from the lifting part of the jack through the previous radial movement of recess 127 away from stub shaft 106 to the position of Fig. 8.

It will thus be observed that I have invented an improved refrigerator unit which is adapted to be used for less than car shipments of perishable goods. The refrigerator unit is provided with a jacking arrangement by means of which the weight may be lifted from the legs, which are provided for the front of the unit, and a car may be loaded very quickly or may be unloaded very quickly.

The jacking arrangement does not take up any space in the car because the jack may be slid backward under the refrigerator into a position where it does not take up any more space than that which the refrigerator unit occupies.

The jack is automatically retained in its forward position when weight is applied to it, but is free to be moved backward when the weight is removed from it. The handle of the jack is adapted to be pivoted freely when the weight is supported on the wheels of the jack or on the front legs of the refrigerator unit.

The weight may be removed from the wheels by merely stepping on the foot pedal of a latch, and there is no possibility of the weight reacting against the handle because at that time the handle has been moved out of operative engagement with the jack mechanism.

The structure of the unit is sturdy, capable of economical manufacture, and adapted to be used for a long period of time without necessity for repair or replacement.

There is no possibility of the jack becoming lost because it is permanently attached to the refrigerator unit.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a portable refrigerator unit, the combination of a refrigerator provided with wheels for supporting one side of the refrigerator and with legs for supporting the other side, with a jack unit slidably mounted on said refrigerator unit, said jack unit including a jack, wheels for supporting the jack, and a handle for actuating the jack, said refrigerator unit having guide means extending along its bottom for slidably supporting the jack, and stop means carried by said guide means and adapted to engage a part of said jack, whereby the jack is prevented from sliding when it is brought into lifting relation with said refrigerator unit.

2. In a portable refrigerator, the combination of a supporting base, said base being provided with a pair of frame members having horizontally extending opposed guide flanges, a slider member slidably mounted between said guide

flanges and carrying a wheel support, said wheel support having a depending frame member, a wheel supporting link pivotally mounted on said depending frame member, and a wheel carried by the other end of said link, and force-multiplying means for moving the wheel supporting end of said link in a downward direction and the other end of said link in an upward direction to take the weight of said refrigerator unit from said wheel and stop means carried by said guide flanges for engaging said slider and preventing its sliding movement when said wheel bears the weight of said refrigerator unit.

3. In a portable refrigerator, the combination of a supporting base, said base being provided with a pair of frame members having horizontally extending opposed guide flanges, a slider member slidably mounted between said guide flanges and carrying a wheeled support, said wheeled support having a depending frame member, a wheel-supporting link pivotally mounted on said depending frame member, and a wheel carried by the other end of said link, and force-multiplying means for moving the wheel supporting end of said link in a downward direction, and the other end of said link in an upward direction to take the weight of said refrigerator unit from said wheel and stop means carried by said guide flanges for engaging said slider and preventing its sliding movement when said wheel bears the weight of said refrigerator unit, said force-multiplying means comprising a handle pivotally mounted at substantially the same center of pivot as said wheel, and a shoulder carried by said depending frame member for engagement with a shoulder on said handle, whereby the handle may be used to pry said link in the direction mentioned above.

4. In a portable refrigerator, the combination of a supporting base, said base being provided with a pair of frame members having horizontally extending opposed guide flanges, a slider member slidably mounted between said guide flanges and carrying a wheeled support, said wheeled support having a depending frame member, a wheel-supporting link pivotally mounted on said depending frame member, and a wheel carried by the other end of said link, and force-multiplying means for moving the wheel supporting end of said link in a downward direction, and the other end of said link in an upward direction to take the weight of said refrigerator unit from said wheel and stop means carried by said guide flanges for engaging said slider and preventing its sliding movement when said wheel bears the weight of said refrigerator unit, said force-multiplying means comprising a handle pivotally mounted at substantially the same center of pivot as said wheel, and a shoulder carried by said depending frame member for engagement with a shoulder on said handle, whereby the handle may be used to pry said link in the direction mentioned above, and latching means for holding said link and wheel in position to support the weight of said refrigerator unit.

5. In a portable refrigerator, the combination of a supporting base, said base being provided with a pair of frame members having horizontally extending opposed guide flanges, a slider member slidably mounted between said guide flanges and carrying a wheeled support, said wheeled support having a depending frame member, a wheel-supporting link pivotally mounted on said depending frame member, and

a wheel carried by the other end of said link, and force-multiplying means for moving the wheel supporting end of said link in a downward direction, and the other end of said link in an upward direction to take the weight of said refrigerator unit from said wheel and stop means carried by said guide flanges for engaging said slider and preventing its sliding movement when said wheel bears the weight of said refrigerator unit, said force-multiplying means comprising a handle pivotally mounted at substantially the same center of pivot as said wheel, and a shoulder carried by said depending frame member for engagement with a shoulder on said handle, whereby the handle may be used to pry said link in the direction mentioned above, said shoulder on said depending frame member comprising a stub shaft for pivotally supporting said link.

6. In a refrigerator unit, the combination of a refrigerator with a jack carried by said refrigerator unit and having wheeled means carried by the jack for supporting the refrigerator unit, said jack including a depending frame member carried by the refrigerator unit and having a transverse shaft, a wheel supporting link having one end mounted on said shaft and having its other end mounted on a wheel shaft, a wheel carried by said wheel shaft, and a handle pivotally mounted on said wheel shaft, said handle having an enlarged aperture surrounding said wheel shaft and having a lifting shoulder whereby the handle may be moved on said wheel shaft into position to bring said shoulder into engagement with the first-mentioned shaft to effect a lifting of the refrigerator unit or the handle may be moved into another position with the shoulder retracted from the first-mentioned shaft for free pivotal movement of the handle.

7. In a refrigerator unit, the combination of a refrigerator with a jack carried by said refrigerator unit and having wheeled means carried by the jack for supporting the refrigerator unit, said jack including a depending frame member carried by the refrigerator unit and having a transverse shaft, a wheel supporting link having one end mounted on said shaft and having its other end mounted on a wheel shaft, a wheel carried by said wheel shaft, and a handle pivotally mounted on said wheel shaft, said handle having an enlarged aperture surrounding said wheel shaft and having a lifting shoulder whereby the handle may be moved on said wheel shaft into position to bring said shoulder into engagement with the first-mentioned shaft to effect a lifting of the refrigerator unit or the handle may be moved into another position with the shoulder retracted from the first-mentioned shaft for free pivotal movement of the handle, and means carried by the handle and acting on said wheel shaft for effecting a lateral shifting of the end of said handle from one position to the other.

8. In a refrigerator unit, the combination of a refrigerator with a jack carried by said refrigerator unit and having wheeled means carried by the jack for supporting the refrigerator unit, said jack including a depending frame member carried by the refrigerator unit and having a transverse shaft, a wheel supporting link having one end mounted on said shaft and having its other end mounted on a wheel shaft, a wheel carried by said wheel shaft, and a handle pivotally mounted on said wheel shaft, said handle having an enlarged aperture surrounding said wheel shaft and having a lifting shoulder where-

by the handle may be moved on said wheel shaft into position to bring said shoulder into engagement with the first-mentioned shaft to effect a lifting of the refrigerator unit or the handle may be moved into another position, with the shoulder retracted from the first-mentioned shaft for free pivotal movement of the handle, and means carried by the handle and acting on said wheel shaft for effecting a lateral shifting of the end of said handle from one position to the other, said means comprising a shift lever movably mounted on said handle and having an enlarged aperture engaging said wheel shaft, the movement of said shift lever relative to said handle causing the handle to move from one position to the other on said wheel shaft.

9. In a refrigerator unit, the combination of a refrigerator with a jack carried by said refrigerator unit and having wheeled means carried by the jack for supporting the refrigerator unit, said jack including a depending frame member carried by the refrigerator unit and having a transverse shaft, a wheel supporting link having one end mounted on said shaft and having its other end mounted on a wheel shaft, a wheel carried by said wheel shaft, and a handle pivotally mounted on said wheel shaft, said handle having an enlarged aperture surrounding said wheel shaft and having a lifting shoulder whereby the handle may be moved on said wheel shaft into position to bring said shoulder into engagement with the first-mentioned shaft to effect a lifting of the refrigerator unit or the handle may be moved into another position, with the shoulder retracted from the first-mentioned shaft for free pivotal movement of the handle, and means carried by the handle and acting on said wheel shaft for effecting a lateral shifting of the end of said handle from one position to the other, said means comprising a shift lever movably mounted on said handle and having an enlarged aperture engaging said wheel shaft, the movement of said shift lever relative to said handle causing the handle to move from one position to the other on said wheel shaft, and means carried by said handle for actuation of said shift lever.

10. In a refrigerator unit, the combination of a refrigerator with a jack carried by said refrigerator unit and having wheeled means carried by the jack for supporting the refrigerator unit, said jack including a depending frame member carried by the refrigerator unit and having a transverse shaft, a wheel supporting link having one end mounted on said shaft and having its other end mounted on a wheel shaft, a wheel carried by said wheel shaft, and a handle pivotally mounted on said wheel shaft, said handle having an enlarged aperture surrounding said wheel shaft and having a lifting shoulder whereby the handle may be moved on said wheel shaft into position to bring said shoulder into engagement with the first-mentioned shaft to effect a lifting of the refrigerator unit or the handle may be moved into another position with the shoulder retracted from the first-mentioned shaft for free pivotal movement of the handle, said enlarged aperture in said handle comprising a pair of partially circular recesses separated by a retaining hump, and said aperture being of sufficient width for the passage of the wheel shaft from one recess to the other.

11. A jack construction for refrigerator car units comprising a wheel frame having a pair

of depending flanges, a shaft carried by said wheel frame and pivotally supporting a pair of metal links, each of said links having an aperture for supporting a wheel shaft at the other end of said links, a handle having a pair of legs, each of said legs being provided with an enlarged aperture surrounding said wheel shaft, said enlarged aperture having a pair of recesses formed in the upper side thereof and said handle legs having an extension provided with a recessed shoulder for engaging said first-mentioned shaft when the handle is in predetermined position, and a shift lever pivotally mounted on said handle and having an oblong aperture surrounding said wheel shaft, said oblong aperture being so arranged that pivotal movement of the shift lever causes the handle to move laterally from one recess to the other on said wheel shaft.

12. A jack construction for refrigerator car units, comprising a wheel frame having a pair of depending flanges, a shaft carried by said wheel frame and pivotally supporting a pair of metal links, each of said links having an aperture for supporting a wheel shaft at the other end of said links, a handle having a pair of legs, each of said legs being provided with an enlarged aperture surrounding said wheel shaft, said enlarged aperture having a pair of recesses formed in the upper side thereof, and said handle legs having an extension provided with a recessed shoulder for engaging said first-mentioned shaft when the handle is in predetermined position, and a shift lever pivotally mounted on said handle and having an oblong aperture surrounding said wheel shaft, said oblong aperture being so arranged that pivotal movement of the shift lever causes the handle to move laterally from one recess to the other on said wheel shaft, and latching means carried by said depending flanges for holding said wheel shaft in weight supporting position.

13. A jack construction for refrigerator car units, comprising a wheel frame having a pair of depending flanges, a shaft carried by said wheel frame and pivotally supporting a pair of metal links, each of said links having an aperture for supporting a wheel shaft at the other end of said links, a handle having a pair of legs, each of said legs being provided with an enlarged aperture surrounding said wheel shaft, said enlarged aperture having a pair of recesses formed in the upper side thereof, and said handle legs having an extension provided with a recessed shoulder for engaging said first-mentioned shaft when the handle is in predetermined position, and a shift lever pivotally mounted on said handle and having an oblong aperture surrounding said wheel shaft, said oblong aperture being so arranged that pivotal movement of the shift lever causes the handle to move laterally from one recess to the other on said wheel shaft, and latching means carried by said depending flanges for holding said wheel shaft in weight supporting position, said latching means being pivotally mounted on said depending flanges, and resilient means for urging said latching means into latching position.

14. A jack construction for refrigerator car units, comprising a wheel frame having a pair of depending flanges, a shaft carried by said wheel frame and pivotally supporting a pair of metal links, each of said links having an aperture for supporting a wheel shaft at the other end of said links, a handle having a pair of legs,

each of said legs being provided with an enlarged aperture surrounding said wheel shaft, said enlarged aperture having a pair of recesses formed in the upper side thereof, and said handle legs having an extension provided with a recessed shoulder for engaging said first-mentioned shaft when the handle is in predetermined position, and a shift lever pivotally mounted on said handle and having an oblong aperture surrounding said wheel shaft, said oblong aperture being so arranged that pivotal movement of the shift lever causes the handle to move laterally from one recess to the other on said wheel shaft, said handle comprising an elongated metal member provided with a pair of legs engaging said wheel shaft, and having a longitudinally extending shift lever rod carried by said handle and slidably mounted thereon for actuating said shift lever.

15. In a chassis for a wheel supported member, the combination of a frame with a plurality of wheels at one end of said frame for supporting that end of the frame, a pair of guides carried by said frame and a wheel support slidably and rotatably mounted on said guides, fixed supporting members carried by said frame at the end opposite to the first-mentioned wheels, a wheel carried by said latter wheel support and connected thereto through the intermediary of a jack, a handle connected to said jack and serving to actuate said jack to lift the frame from said fixed supports to be supported on said latter wheel, said handle also serving as a controlling member for pulling, pushing or turning said latter wheel, said wheel support being mounted for free sliding movement on said guides when said frame is carried by said fixed supporting members, and said wheel support having a predetermined vertical movement with respect to said guides, and stop means carried by said guides behind said wheel support at its foremost position whereby the wheel support engages said stop means and is secured against sliding movement when said wheel support is lifted by said jack into engagement with said guides in front of said stop means.

16. In a jack construction the combination of a frame member adapted to be supported by a wheel, said frame member having a link pivoted thereon and said link having at its opposite end a shaft carrying said wheel, with a handle member pivotally mounted on said latter shaft, said handle member having an elongated portion for use in actuating said jack and having at its opposite end a rearwardly extending lifting shoulder, means carried by said frame member for engagement with said lifting shoulder when said handle is pivoted downwardly on said shaft to a predetermined point, said handle urging said shaft downwardly on said link to cause said wheel to lift said frame member.

17. In a jack construction the combination of a frame member adapted to be supported by a wheel, said frame member having a link pivoted thereon and said link having at its opposite end a shaft carrying said wheel, with a handle member pivotally mounted on said latter shaft, said handle member having an elongated portion for use in actuating said jack and having at its opposite end a rearwardly extending lifting shoulder, means carried by said frame member for engagement with said lifting shoulder when said handle is pivoted downwardly on said shaft to a predetermined point, said handle urging said shaft downwardly on said link to cause said wheel to lift said frame member, and latch-

ing means carried by said frame member, said latching means having a shoulder for engaging said shaft when said wheel and link are moved downwardly into the position to support said frame member.

18. In a jack construction the combination of a frame member adapted to be supported by a wheel, said frame member having a link pivoted thereon and said link having at its opposite end a shaft carrying said wheel, with a handle member pivotally mounted on said latter shaft, said handle member having an elongated portion for use in actuating said jack and having at its opposite end a rearwardly extending lifting shoulder, means carried by said frame member for engagement with said lifting shoulder when said handle is pivoted downwardly on said shaft to a predetermined point, said handle urging said shaft downwardly on said link to cause said wheel to lift said frame member, latching means carried by said frame member, said latching means having a shoulder for engaging said shaft when said wheel and link are moved downwardly into the position to support said frame member, and resilient means acting between said latch and frame member for urging said latch into the latching position.

19. In a jack construction the combination of a frame member adapted to be supported by a wheel, said frame member having a link pivoted thereon and said link having at its opposite end a shaft carrying said wheel, with a handle member pivotally mounted on said latter shaft, said handle member having an elongated portion for use in actuating said jack and having at its opposite end a rearwardly extending lifting shoulder, means carried by said frame member for engagement with said lifting shoulder when said handle is pivoted downwardly on said shaft to a predetermined point, said handle urging said shaft downwardly on said link to cause said wheel to lift said frame member, latching means carried by said frame member, said latching means having a shoulder for engaging said shaft when said wheel and link are moved downwardly into the position to support said frame member, and resilient means acting between said latch and frame member for urging said latch into the latching position, said latch having an extension for engagement with the foot of the operator and said latch moving in a downward direction to effect a release of the said shaft.

20. In a jack construction the combination of a frame member adapted to be supported by a wheel, said frame member having a link pivoted thereon and said link having at its opposite end a shaft carrying said wheel, with a handle member pivotally mounted on said latter shaft, said handle member having an elongated portion for use in actuating said jack and having at its opposite end a rearwardly extending lifting shoulder, means carried by said frame member for engagement with said lifting shoulder when said handle is pivoted downwardly on said shaft to a predetermined point, said handle urging said shaft downwardly on said link to cause said wheel to lift said frame member, said handle having an elongated aperture engaging said shaft whereby the handle may be moved into one position with its lifting shoulder engaging said means on said frame member or another position where its lifting shoulder passes said latter means.

21. In a jack construction the combination of 75

a frame member adapted to be supported by a wheel, said frame member having a link pivoted thereon and said link having at its opposite end a shaft carrying said wheel, with a handle member pivotally mounted on said latter shaft, said handle member having an elongated portion for use in actuating said jack and having at its opposite end a rearwardly extending lifting shoulder, means carried by said frame member for engagement with said lifting shoulder when said handle is pivoted downwardly on said shaft to a predetermined point, said handle urging said shaft downwardly on said link to cause said wheel to lift said frame member, said handle having an elongated aperture engaging said shaft whereby the handle may be moved into one position with its lifting shoulder engaging said means on said frame member or another position where its lifting shoulder passes said latter means, and latching means carried by said handle for holding said handle in either of its said positions with respect to said shaft.

22. In a jack construction the combination of
a frame member adapted to be supported by a
wheel, said frame member having a link piv-
oted thereon and said link having at its opposite
end a shaft carrying said wheel, with a handle
member pivotally mounted on said latter shaft,
said handle member having an elongated por-
tion for use in actuating said jack and having
at its opposite end a rearwardly extending lifting
shoulder, means carried by said frame member
for engagement with said lifting shoulder when
said handle is pivoted downwardly on said shaft
35 to a predetermined point, said handle urging said
shaft downwardly on said link to cause said
wheel to lift said frame member, said handle
having an elongated aperture engaging said
shaft whereby the handle may be moved into
40 one position with its lifting shoulder engaging
said means on said frame member or another
position where its lifting shoulder passes said
latter means, and latching means carried by said
handle for holding said handle in either of its
45 said positions with respect to said shaft, said
latching means comprising a member pivoted
on said handle and having an elongated opening
surrounding said shaft, said opening having walls
defining two shaft-retaining positions.

50 23. In a jack construction the combination of
a frame member adapted to be supported by a
wheel, said frame member having a link pivoted
thereon and said link having at its opposite
end a shaft carrying said wheel, with a handle
55 member pivotally mounted on said latter shaft,
said handle member having an elongated por-
tion for use in actuating said jack and having
at its opposite end a rearwardly extending lift-
ing shoulder, means carried by said frame mem-
60 ber for engagement with said lifting shoulder
when said handle is pivoted downwardly on said
shaft to a predetermined point, said handle urging
said shaft downwardly on said link to cause
said wheel to lift said frame member, said han-
65 dle having an elongated aperture engaging said
shaft whereby the handle may be moved into one
position with its lifting shoulder engaging said
means on said frame member or another pos-
ition where its lifting shoulder passes said latter
70 means, latching means carried by said handle
for holding said handle in either of its said po-
sitions with respect to said shaft, said latching
means comprising a member pivoted on said han-
75 dle and having an elongated opening surround-
ing said shaft, said opening having walls de-

fining two shaft-retaining positions, and a latch-actuating handle pivotally connected to said latter member and slidably mounted on said handle.

24. In a movable vehicle, the combination of a chassis frame with a plurality of wheel brackets carried by said frame and located toward one end of the frame, wheels rotatably mounted on said brackets for movably supporting this end of the vehicle, a guide extending toward the other end of said vehicle and carried by the lower part of said chassis frame, a slider slidably mounted on said guide, a wheel bracket pivotally mounted on said slider for pivotal movement of the wheels to be carried thereby in steering the vehicle, a wheel carried by said latter bracket and connected thereto by means of a jack, fixed and stable supporting means carried by said other end of said chassis frame so that this end of the frame may be supported on said fixed and stable supporting means or on said pivoted wheel, and a handle carried by said jack and adapted to be used for pulling the vehicle and steering it, and for actuating the jack to lift that end of the chassis frame from said fixed supporting means and place its weight upon said pivoted wheel, said guides being of predetermined length with respect to the length of said handle, so that the jack may be slid backward on said guides by means of said slider until the handle is disposed substantially beneath the chassis.

25. In a movable vehicle, the combination of a chassis frame with a plurality of wheel brackets carried by said frame and located toward one end of the frame, wheels rotatably mounted on said brackets for movably supporting this end of the vehicle, a guide extending toward the other end of said vehicle and carried by the lower part of said chassis frame, a slider slidably mounted on said guide, a wheel bracket pivotally mounted on said slider for pivotal movement of the wheels to be carried thereby in steering the vehicle, a wheel carried by said latter bracket and connected thereto by means of a jack, fixed and stable supporting means carried by said other end of said chassis frame so that this end of the frame may be supported on said fixed and stable supporting means or on said pivoted wheel, and a handle carried by said jack and adapted to be used for pulling the vehicle and steering it, and for actuating the jack to lift that end of the chassis frame from said fixed supporting means and place its weight upon said pivoted wheel, said pivoted wheel being slidable under said guides to a position under said chassis, and said guides having a stop member located to engage said slider and prevent the sliding movement of the slider on said guides, when the slider is disposed beyond the stop member, and the pivoted wheel is supporting the weight of the vehicle.

26. In a movable vehicle, the combination of a chassis frame with a plurality of wheel brackets carried by said frame and located toward one end of the frame, wheels rotatably mounted on said brackets for movably supporting this end of the vehicle, a guide extending toward the other end of said vehicle and carried by the lower part of said chassis frame, a slider slidably mounted on said guide, a wheel bracket pivotally mounted on said slider for pivotal movement of the wheels to be carried thereby in steering the vehicle, a wheel carried by said latter bracket and connected thereto by means of a jack, fixed and stable supporting means carried by said other end of said chassis frame so that this end of the frame may be supported on said fixed and stable supporting means or on said pivoted wheel, and a handle carried by said jack and adapted to be used for pulling the vehicle and steering it, and for actuating the jack to lift that end of the chassis frame from said fixed supporting means and place its weight upon said pivoted wheel, said pivoted wheel being slidable under said guides to a position under said chassis, and said guides having a stop member located to engage said slider and prevent the sliding movement of the slider on said guides, when the slider is disposed beyond the stop member, and the pivoted wheel is supporting the weight of the vehicle, said slider having a predetermined lost motion in a vertical direction between its parts and the parts of said guides, whereby the lower part of the slider hangs below said stop member when the weight of the vehicle is removed from said pivoted wheel, so that the slider clears and is adapted to pass the stop member to permit the jack and handle to be shoved under the vehicle.

27. In a portable refrigerator unit, the combination of a refrigerator provided with wheels for supporting one side of the refrigerator and with legs for supporting the other side, with a jack unit slidably mounted on said refrigerator unit, said jack unit including a jack, wheels for supporting the jack, and a handle for actuating the jack, said refrigerator unit having guide means extending along its bottom for slidably supporting the jack, and stop means carried by said guide means and adapted to engage a part of said jack, whereby the jack is prevented from sliding when it is brought into lifting relation with said refrigerator unit, said jack having a lost motion slidable connection to said guide means for lost motion in a vertical direction, and said stop means being located on the lower side of said guide means and being of predetermined vertical dimension with respect to said lost motion, to permit the jack parts below the guide means to slide under said stop means when the jack parts depend from the guide means without supporting weight.

CHARLES S. JOHNSTON.
